UNITED STATES PATENT OFFICE.

STAFFORD LIGHTBURNE, JR., OF ST. LOUIS, MISSOURI.

GASOLINE-STOVE ATTACHMENT.

SPECIFICATION forming part of Letters Patent No. 372,544, dated November 1, 1887.

Application filed January 19, 1885. Serial No. 153,220. (No model.)

To all whom it may concern:

Be it known that I, STAFFORD LIGHTBURNE, Jr., of the city of St. Louis, in the State of Missouri, have invented a certain new and useful Improvement in Gasoline-Stove Attachments, of which the following is a full, clear, and exact description, reference being had to the accompanying drawings, forming part of this specification, and in which—
10. Figure 1 is an elevation of a gasoline-stove with my improvement applied. Fig. 2 is a top view. Fig. 3 is a section of the stove-top, taken on line 3 3, Fig. 4, showing the dial in end view enlarged. Fig. 5 is a similar view taken on line 5 5, Fig. 4, showing the other end of the dial. Fig. 6 is a section of the top, taken on line 4 4, Fig. 3, showing the face or front of the dial. Fig. 7 is a detail view taken on the line 6 6, Fig. 1, enlarged. Fig. 8 is a detail view taken on the line 7 7, Fig. 1, enlarged.

My invention relates to an attachment for gasoline or vapor stoves, whereby the flow of oil through the supply-pipe is indicated and the heat of the burner determined; and my improvement consists in features of novelty hereinafter fully described, and pointed out in the claims.

Referring to the drawings, A represents a gasoline-stove frame; A', the supply-pipe; A", the burner, and A''' the valve-rod, to which, *per se*, I make no claim as inventor. Depending from the top or otherwise connected to the stove are dial-plates B, having numbered 25 graduations or other signs, C.

D are indicators or fingers on the valve-stems pointing to the graduations or signs for indicating the open, closed, or intermediate positions of the valves, so as to inform the attendant of the approximate amount of heat produced when the burners are in use, as well as to indicate whether the burners are open or shut. This amount will be made known to purchasers of the stoves by a book of instructions or otherwise.

If the fingers D (which are secured to and by which the valve-rods of the burners are operated) are each turned, say, to the numeral 8, the burner will give out a certain amount 30 of heat, or if turned to the numeral 9 a certain amount more will be given out, or if to

the numeral 7 a certain amount less will be produced. Each finger D has an extension, I, for a finger-hold to assist in turning the valves. Each plate has a slot or opening, J, 55 in which fits an adjustable pin or stop, L, held by a thumb-screw, M, against which the finger comes when the valve is closed, so that the person will know when the valve is closed. It will be seen that the pin can be moved or 60 adjusted in either direction to agree with the position of the finger on the valve-stem.

Secured to each plate B behind the slot J is another plate, N, the plate being connected by a set-screw, O, fitting in a slot, P. (Shown 65 by dotted lines, Fig. 4.) This second plate has numbered graduations or other signs, the finger pointing thereto indicating approximately the amount of heat in the oven of the stove, so that by adjusting the plate to suit 70 the burners used, and turning the finger to, say, 150, that many degrees of heat will be had in the oven.

The finger is secured to the valve-stem by a set-screw, V, so that it may be adjusted relative to the numbers on the dial-plate without turning the valve, so that the valve will be opened more or less when the finger is moved to any given number, and when the finger is moved on the stem the pin L is adjusted 80 accordingly, so that the finger will come against it as a stop when the valve is closed.

I claim as my invention—

1. The combination, with a gasoline-stove having a burner provided with a valve and valve-stem, of a dial-plate suspended from the stove, supporting the valve-stem, having a series of numbered graduations, and a combined handle and indicator-finger on the valve-stem of the burner working over the face of 85 the dial-plate, substantially as described and shown.

2. The combination, with a gasoline stove, of a dial-plate having upper and lower series of numbered graduations, and a combined 90 handle and finger on the valve-stem of the burner, substantially as set forth.

3. The combination, with a gasoline-stove, of a dial-plate having graduations and slots, a combined handle and finger secured to the 95 valve-stem of the burner, and an adjustable plate having graduations secured to the dial-

plate and exhibiting its graduations through the slots of the dial-plate, substantially as set forth.

4. The combination, with a gasoline-stove, of a dial-plate having graduations and slots, pin adjustable in a slot, rear plate having graduations and a slot, set-screw securing the

rear plate to the dial-plate, and a combined handle and finger secured to the valve-stem of a burner, substantially as set forth.

STAFFORD LIGHTBURNE, JR.

In presence of—

GEO. H. KNIGHT,
SAML. KNIGHT.
